(57) CLAIM

The ornamental design for a combined lunch box and integrated canteen, as shown and described.

DESCRIPTION

FIG. 1 is a perspective view of a combined lunch box and integrated canteen;

FIG. 2 is a front view thereof, the rear view being a mirror image thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof, with the lunch box in an open position and the integrated canteen removed therefrom.
